UNITED STATES PATENT OFFICE.

HERMAN C. MAISE, OF DETROIT, MICHIGAN, ASSIGNOR TO BRIGGS MANUFACTURING COMPANY, OF DETROIT, MICHIGAN, A CORPORATION OF MICHIGAN.

SUPPORT FOR DOOR BUMPERS.

Application filed October 8, 1923. Serial No. 667,423.

This invention relates to vehicle bodies and refers more particularly to supports for door buffers and the like.

An object of the invention is to provide a post or pillar having portions that form jambs for a plurality of doors and that preferably cooperate with a reinforcing member for the post to support a plurality of yieldable cushion members which form buffers for said doors.

Another object is to provide a reliable and practical construction that is capable of holding the doors closed against the jambs and that is also capable of preventing rattling.

Another object is to provide a strong and durable construction that can be manufactured at a comparatively low cost.

With the above and other objects in view the invention consists in certain novel features of construction, combination and arrangement of parts as will be more fully described and particularly pointed out in the appended claims.

In the accompanying drawing:

Figure 1 is a fragmentary side elevation of a vehicle body embodying my invention;

Figure 2 is a sectional view taken on line 2-2 of Figure 1;

Figure 3 is an enlarged fragmentary elevation of the post embodying my invention;

Figure 4 is a sectional view taken on line 4-4 of Figure 2;

Figure 5 is a detail perspective view of one of the buffers;

Figure 6 is a perspective view of the reinforcing member.

Referring now to the drawing in which like characters of reference designate corresponding parts throughout the several views, the numeral 1 designates a motor vehicle body having a metallic post or pillar 2 and a pair of doors 3 that are normally disposed in closed position against opposite sides of the post.

The post is preferably hollow and is preferably provided with a longitudinally extending forwardly projecting portion 4 that is preferably channel-shape in cross-section and that is preferably provided with laterally extending wings or flanges 5 which connect into the forwardly diverging sides 6 of the post. The rear wall 7 of the post is preferably formed separately and is preferably provided with marginal flanges 8 that

are secured to the sides 6 adjacent to the rear edges thereof.

Located in the post, preferably about midway of its length, is a reinforcing member 9 therefor. This reinforcing member preferably extends transversely of the post and is preferably formed from sheet metal which is bent as shown, providing a pair of spaced pockets 10 having marginal flanges 11 that are secured to the sides 6 of the post. These pockets preferably register with elongated openings 12 in the post at the opposite sides thereof and preferably cooperate with the sides 6 and flanges 5 to support a pair of buffers 13 for the doors.

Each buffer preferably consists of a pair of elongated resilient cushion members 14 that are preferably spaced apart so that portions thereof project slightly above and below the edges of the openings 12. Wear plates 15 are preferably provided between the cushion members of the buffers and are preferably return-bent as shown to provide spaced arms 16 that retain the cushion members firmly in engagement with the top and bottom of the pockets. These arms are preferably bent in opposite directions at their outer ends as shown at 17 and are adapted to receive elongated tongues 18 projecting outwardly from the forward edges of the doors. The tongues are preferably constructed of sheet metal and are preferably of such thickness that they frictionally engage the arms 16 and thus prevent rattling when the doors are closed.

If desired, the frictional engagement between the tongues and arms may be such that the buffers will be capable of holding the doors in closed position.

While it is believed that from the foregoing description the nature and advantages of the invention will be readily apparent, I desire to have it understood that I do not limit myself to what is herein shown and described and that such changes may be resorted to when desired as fall within the scope of what is claimed.

What I claim as my invention is:

1. In a vehicle body, the combination with a hollow post having a transversely extending opening in one wall thereof, of a sheet metal reinforcing member for the post having a pocket cooperating with a wall of the post to form a housing, one end of said pocket being open and in communication

with the opening in the post, door buffers in the housing, said buffers being spaced apart to receive a projection on a door, and a wear plate between said buffer members normally holding the same spaced apart against opposite walls of the pocket.

2. In a vehicle body, a hollow post having openings in opposite sides thereof, a reinforcing member extending transversely of the post and having spaced pockets inside the post registering with said openings and having marginal flanges secured to the adjacent walls of said post, said pockets being of a greater area than said openings, whereby portions of said reinforcing member overlap the adjacent edge portion of said openings and thereby providing housings with the post for door buffers and the like.

3. In a vehicle body, the combination with a hollow post having transversely extending openings in opposite walls thereof, of a reinforcing member extending transversely of

the post having spaced pockets cooperating with opposite walls of the post to form housings, one end of said pockets being open and communicating with the openings in the post, and yieldable cushion elements in said housings.

4. In a vehicle body the combination with suitable doors and tongues projecting therefrom, of a door post provided with a longitudinally extending channel-shaped portion and diverging side walls, a metallic reinforcing member extending transversely of the post having pockets cooperating with said diverging sides to form housings for door buffers, and lateral wings connecting the sides of the channel-shaped portion to the diverging sides of the post, said wings and diverging walls having communicating openings therein for receiving said tongues.

In testimony whereof I affix my signature.

HERMAN C. MAISE.
